UNITED STATES PATENT OFFICE.

OSCAR P. NYSTROM, OF HOLLAND, MICHIGAN, ASSIGNEE TO HOLLAND FURNACE COMPANY, OF HOLLAND, MICHIGAN.

WARM-AIR FURNACE.

Application filed October 24, 1927. Serial No. 228,292.

This invention relates particularly to the feed door construction of furnaces.

The object of the invention is to provide a feed door construction which can be readily adjusted in place so that the door shall accurately fit the flange of the door opening.

Objects pertaining to details and economies of my invention will definitely appear from the description to follow.

10 I accomplish the objects of my invention by the devices and means described in the following specification. The invention is clearly defined and pointed out in the claims.

15 A device embodying my invention is clearly illustrated in the accompanying drawing forming a part of this application, in which:

Fig. 1 is a perspective view of the main casting of the furnace, with my improved feed door structure in place.

Fig. 2 is a detail front elevation of the door frame and door.

Fig. 3 is an enlarged detail plan view of the parts appearing in Fig. 1.

25 Fig. 4 is a detail view in section taken on line 4—4 of Figs. 3 and 5, the section being through the retaining bolts.

Fig. 5 is an enlarged detail sectional view on line 5—5 of Figs. 2, 3 and 4 through one 30 of the adjusting clamping bolts.

Fig. 6 is an enlarged detail sectional view on line 6—6 of Figs. 2, 3 and 4 through one of the adjusting set screws.

The parts will be identified by their numbers of reference which are the same in all the views.

1 is the fire pot of the furnace. 2 is the combustion chamber. 3 is the feed intake passage terminating in the door opening 4 which presents preferably a ground joint surface at the front. The furnace casting forming the intake passage is provided with central upward and downward projecting lugs 5 and slotted lugs 6 at each side above and below the door opening for attachment and adjustment of the door frame. 7 is the door frame on which is hinged the door 8.

9 is the door latch carried by the door frame. 61, 61 are the attaching bolts for the door frame, one at each side, being disposed through the frame 7 and the slotted lugs 6. 51 are the adjusting set screws through nuts 52 for adjusting accurately the position of the door frame, in cooperation with the attaching bolts 61. 55

From this it will be seen that the door with its ground face to correspond with the ground joint of the door opening in the casting can be effectively and accurately adjusted in place before the joints are cemented. This is done by putting the door in place, adjusting the set screws 51 and drawing up the attaching bolts and adjusting said bolts and screws until the desired result is attained. The joints about the frame can 65 then be cemented or packed if desired.

Having thus described my invention what I claim as new and desire to secure by Letters Patent is:

1. In a furnace door structure, a combustion chamber casting with feed passage, a door opening therefor with ground joint, central lugs and lateral slotted lugs above and below said door opening, a door frame, a door hinged thereto with ground joint, 70 clamping bolts disposed through the lateral slotted lugs, and a central set screw cooperating therewith for adjustment of the same, as specified. 75

2. In a furnace door structure, the combination of a combustion chamber casting with a door opening with ground joint surface at the front, a door frame with ground joint surface corresponding to said ground joint surface at the front of said combustion chamber and adapted to cooperate therewith, means to adjustably attach said frame comprising lateral clamp bolts and intermediate set screws, and a door hinged to said door frame, as specified. 85 90

In witness whereof I have hereunto set my hand.

OSCAR P. NYSTROM.
